UNITED STATES PATENT OFFICE.

DAVID PALMER, OF CHICAGO, ILLINOIS.

CIGARETTE-HOLDER.

1,391,071.

Specification of Letters Patent. Patented Sept. 20, 1921.

Application filed June 28, 1920. Serial No. 392,255.

To all whom it may concern:

Be it known that I, DAVID PALMER, a citizen of the United States, residing at Chicago, in the county of Cook and State of Illinois, have invented a new and useful Improvement in Cigarette-Holders, of which the following is a specification.

My invention relates to cigar and cigarette holders, and has for its objects the provision of a holder into which the article may be readily and quickly inserted and lightly but securely held without danger of injuring the paper or wrapper, and which is so light in weight that it may be left upon the cigar or cigarette while the cigar or cigarette is held or supported between the lips of the smoker without the additional weight being perceived. Another object is the provision of a holder that is made of a single or integral piece of material and so formed that it may be readily latched or released with one hand, if desired, and whereby a spring loops is provided for clamping the cigarette. By closing the spring loop the holder will readily conform to the shape or size of the cigarette by reason of the interposition of the comparatively long standard and arm between the holding portion and the latch, and will lightly compress the filling material so that the loose ends will be prevented from working out of the end of the cigarette into the smoker's mouth. Also, I have provided the spring loop with a flattened or weakened portion rendering the same more flexible to avoid rupturing the wrapper and permitting the more complete conformation to the cross-sectional contour of the cigarette. Other objects will be apparent after a more complete understanding of my invention is had, and I prefer to carry out these divers objects in substantially the manner hereinafter fully described, and as particularly pointed out in the claims.

Reference will now be made to the accompanying drawings that form a portion of this specification which, in a sense, are merely diagrammatic for the purpose of illustration.

In the drawings:

Figure 1 is a perspective view of the holder showing the same in use with a cigarette.

Fig. 2 is an elevation of the holder showing the arms latched.

Fig. 3 is a view similar to Fig. 2 showing

the arms released for the insertion of a cigarette.

Fig. 4 is a fragmental view slightly enlarged of the upper or looped portion of the holder. 60

Similar reference characters are employed to designate the same parts throughout the view of the drawings, and by referring to the latter it will be seen I form my improved holder of a single or integral 65 piece of wire of either round or flattened cross-section, one end whereof is bent into a circular or ring-shaped finger grasp or handle 1 by which the device may be easily grasped between two of the smoker's fingers. 70 From the handle 1 the remaining portion extends outwardly or upwardly in a radial direction to provide a standard 2 that is substantially straight (see Fig. 3), and at its outer or upper end the standard is shaped 75 into a single loop 3 that is closed at its outer segment, as shown, and is preferably elliptical in outline.

After forming loop 3, the wire is continued downwardly into another straight 80 piece or arm 4, corresponding substantially with standard 2 and at its inner or lower end is bent around and laterally into a small hook or latch element 5. The plane of the body of hook 5 is preferably slightly oblique to the plane of the holder structure, and when in position, shown in Fig. 3, this hook extends away or outwardly from the holder structure. This permits arm 4 to be moved laterally toward and past the 85 standard so that when the pressure of the fingers is released the hook and adjacent portion of arm 4 will engage the adjacent part of the standard to latch the holder in position to secure or clamp the cigarette. 90 95

In inserting the cigarette or other article the device is opened, as indicated in Fig. 3, so that an entrance or mouth to loop 3 is provided between the adjacent portions of standard 2 and element or arm 4 and the 100 cigarette is guided between the sides of this mouth into the loop after which arm 4 is moved back toward and past standard 2 so that the latch 5 may engage the latter, and thus hold or clamp the cigarette in the 105 loop. For the purpose of rendering this loop more flexible, besides providing standard 2 and arm 4, which give considerable flexibility, I have also reduced the thickness of the wire, as at 6, by flattening it or other- 110

wise which permits the loop to engage the cigarette and more readily conform to the shape thereof.

I am aware that holders have heretofore been made wherein the loop is open at its outer portion and is adapted to be constricted into a gripping position by a movable or slide ring, but my structure has a much more resilient and secure grasp and is free from the liability of rupturing the paper or wrapper of the cigarette or cigar with the outwardly opening ends of the loop.

What I claim new is:

1. A cigarette holder comprising an elongated piece of metal bent intermediate its ends to provide a resilient loop to receive the cigarette, the portions of the metal extending from the loop forming respectively

a standard providing means whereby the device may be held by the smoker, and an arm 20 having a latch element whereby the same may be engaged with the standard to retain the article in the loop.

2. A cigarette holder comprising an elongated piece of metal bent intermediate its 25 ends to provide a resilient loop to receive the cigarette, the metal forming the loop having flattened areas to increase the resiliency of the loop, the portions of the metal extending from the loop forming respectively 30 a standard providing means whereby the device may be held by the smoker, and an arm having a latch element whereby the same may be engaged with the standard to retain the article in the loop.

DAVID PALMER.
